[57] CLAIM

The ornamental design for a combined brush and sponge shaving cream applicator, as shown and described.

DESCRIPTION

FIG. 1 is a side elevational view of the combined brush and sponge shaving cream applicator, the opposite side being a mirror image thereof. The broken lines illustrating a can of shaving cream are for illustrative purposes and form no part of the claimed design;

FIG. 2 is a front elevational view thereof;

FIG. 3 is a rear elevational view thereof;

FIG. 4 is a top plan view thereof; and,

FIG. 5 is a bottom plan view thereof.

The sponge surface pattern and the bristles are partially shown for ease of illustration and are understood to repeat along the areas indicated.
